UNITED STATES PATENT OFFICE.

HARRY D. OGDEN, OF PHILADELPHIA, PENNSYLVANIA.

DESIGN FOR A BICYCLE CRANK-ARM.

SPECIFICATION forming part of Design No. 31,008, dated June 13, 1899.

Application filed May 19, 1899. Serial No. 717,507. Term of patent 31 years.

To all whom it may concern:

Be it known that I, HARRY D. OGDEN, a resident of the city and county of Philadelphia, Pennsylvania, have invented and produced a new and original Design for Bicycle Crank-Arms, of which the following is a specification, reference being had to the accompanying drawings.

In the drawings, Figure 1 is a side elevation showing my new design. Fig. 2 is a section on line C D of Fig. 1. Fig. 3 is a section on line A B of Fig. 1.

As shown in the drawings, the leading or material feature of my design is in having a bell-shaped crank-arm with grooves *d d* or ridges running longitudinally. These grooves

or ridges extend concentrically around an aperture O at the center of the angular turn. At the point *e* where the foot-tread stud is secured to the crank-arm the face is left plain.

Having now described my invention, what I claim as new, and desire to secure by Letters Patent, is—

The design of a crank-arm, as herein shown and described.

In testimony of which invention I hereunto set my hand.

HARRY D. OGDEN.
